Primary Examiner — Darlington Ly*Assistant Examiner* — D. Ryan Tisdale(74) *Attorney, Agent, or Firm* — Vichit Chea(57) **CLAIM**

The ornamental design for a vehicle front lower bumper cover, as shown and described.

DESCRIPTION

FIG. 1 is a front elevational view of a vehicle front lower bumper cover, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a bottom, front and left side perspective view thereof; and,

FIG. 7 is a top, front and left side perspective view thereof. The ghosted or low contrasted showing of the vehicle front lower bumper cover is provided for the purposes of illustrating environmental structure and forms no part of the claimed design.
